US00D524281S

(12) **United States Design Patent** (10) **Patent No.:** **US D524,281 S**
Franck et al. (45) **Date of Patent:** **** Jul. 4, 2006**

(54) **TELEPHONE HEADSET**

(75) Inventors: **Christopher G. Franck**, Decatur, GA (US); **Jeffery R. Beasley**, Suwanee, GA (US); **Matthew M. Julian**, Sunrise, FL (US)

(73) Assignee: **General Instrument Corporation**, Horsham, PA (US)

(**) Term: **14 Years**

(21) Appl. No.: **29/224,518**

(22) Filed: **Mar. 3, 2005**

(51) **LOC (8) Cl.** **14-03**

(52) **U.S. Cl.** **D14/147**

(58) **Field of Classification Search** **D14/137, D14/138, 147-148, 247-248, 144, 218, 341-347; 379/433.01-433.13, 434; D13/168; D21/517; 455/556.1, 556.2, 566, 575.1, 90.3**
